UNITED STATES PATENT OFFICE.

ORRIE C. STROHM, OF PHILADELPHIA, PENNSYLVANIA, ASSIGNOR TO MORTIMER W. SMITH, OF CAMDEN, NEW JERSEY.

ALARM.

1,206,939.

Specification of Letters Patent.

Patented Dec. 5, 1916.

Application filed August 26, 1915. Serial No. 47,392.

To all whom it may concern:

Be it known that I, ORRIE C. STROHM, a citizen of the United States, residing in the city of Philadelphia, county of Philadelphia, State of Pennsylvania, have invented a new and useful Alarm, of which the following is a specification.

My invention relates to a new and useful alarm for burglars and others and consists 10 of means for holding a cartridge and for discharging the same, means for preventing the cartridge from being thrown from the device and means for preventing injury from the discharge.

15 It further consists of novel features all as will be hereinafter set forth.

For the purpose of illustrating my invention, I have shown in the accompanying drawing one form thereof which is at 20 present preferred by me, since the same will give in practice satisfactory and reliable results, although it is to be understood that the various instrumentalities of which my invention consists are variously arranged 25 and organized and that my invention is not limited to the precise arrangement and organization of these instrumentalities as herein shown and described.

Figure 1 is a perspective view of an 30 alarm device showing the same in position with a portion of a window frame and window sash broken away. Fig. 2 is a sectional view on the line $x-x$ Fig. 1. Fig. 3 is a sectional view on the line $y-y$ Fig. 2, 35 in detached position. Fig. 4 is an end elevation of the alarm in detached position.

Similar numerals of reference indicate corresponding parts in the figures.

Referring to the drawings, 1 designates 40 a window sill, to which as here shown, my alarm is secured, and 2 designates a portion of a window sash, which it is to guard. The alarm comprises a casing 3 of any suitable construction having an open side 4, the bottom wall 5 being adapted to be secured in any desired manner to a suitable support. In the drawing I have shown holes adapted to receive screws 6 or other fastening means for securing the casing in position preferably with the open side 4 against a suitable portion of the window sash. Suitable means is provided for supporting the cartridge and, as shown, the upper wall 7 is provided with a suitable opening 8 adapted to receive and hold the cartridge 9 with the rim

of the head 10 thereof resting upon said upper wall. 11 designates a hammer which is composed of a resilient member, here shown as a flat spring, rotatably or swingingly mounted, as by a pivot 12, upon the upper face or wall 7 and having an end 13 extending beyond the end of the casing 3.

14 designates a pin carried by the resilient member 11 for firing the cartridge.

15 designates a safety device here shown as a cap or slide, which is movably or slidably mounted upon the upper wall 7 of the casing, in order that it can be moved from the opening 8 to permit insertion of a cartridge 9 and thereafter returned to operative position said cap having in the underside of its top member a suitable recess 16 in which the head 10 of the cartridge is seated when the slide is in operative position. The cap is also provided with an opening 17 which when in operative position is suitably located with respect to or in line with the head of the cartridge and through which the firing pin 14 passes when firing or discharging the cartridge. 80

It will be understood that the slide is suitably connected with or mounted upon the casing 3, in order that while being capable of being moved away from the opening 8 it cannot be detached or removed therefrom and, in the present instance, I have shown lugs, beads or guiding members 18 on the casing, which are engaged by the inwardly extending flanges or ears 19 on the slide, as will be best understood from Fig. 3. 20 90

21 designates a stop on the casing against which the end of the slide is adapted to abut to limit its movement and to insure that it will be properly located in operative position.

21 designates a pin or other suitable abutment carried by the window sash 2 and which is normally beneath the extending end 13 of the resilient member 11. 95

The operation of the device is as follows:—The casing having been secured to the window sill when it is desired to set the alarm, the resilient member 11 is swung or rotated outwardly to one side as in the direction of the arrow Fig. 3 and the slide 15 is moved along the top wall 7 of the casing exposing the opening 8 into which a cartridge is dropped. The slide 15 is then moved back over the cartridge, the head of which is seated in the recess 16; and the resilient member 11 is moved back to its 100 105 110

normal position, as seen in Figs. 1 and 2, with the firing pin 14 in line with the head of the cap and with the end 13 of the member 11 extending over the pin 21. If 5 the window sash is now elevated, the pin 21 will raise the free end 13 of the resilient member 11 until the said pin 21 passes or releases it and, when released or tripped, the member 11 will spring down 10 impelling the firing pin 14 forcibly against the cap striking and discharging the same. By the employment of the slide 15 it will be seen that the cap will be prevented from being thrown out of the opening 8 and it 15 will also prevent any of the powder, wadding or products of explosion from injuring anyone and the smoke, etc., can escape through the open side after the cartridge is discharged through the opened window. 20 It will be further apparent should the cartridge be accidentally discharged by anyone improperly raising the resilient member 11 that by reason of the construction injury to the person will be prevented. 25 Should, through any inadvertence, a cartridge having a bullet therein, be placed in the device, the closed casing and safety cap will prevent the bullet from striking or injuring anyone. 30 It will be understood that while I have shown the device in position with respect to a window, it is, of course, applicable to doors, as well, and while I have shown the same as connected with the window sill, it 35 can be otherwise supported in order to be operative.

It will now be apparent that I have de-

vised a novel and useful construction of an alarm which embodies the features of advantage enumerated as desirable in the 40 statement of the invention and the above description, and while I have, in the present instance, shown and described a preferred embodiment thereof which will give in practice satisfactory and reliable results, 45 it is to be understood that the same is susceptible of modification in various particulars without departing from the spirit or scope of the invention or sacrificing any of its advantages. 50

Having thus described my invention, what I claim as new and desire to secure by Letters Patent, is:—

In a burglar alarm, an open-sided casing adapted to be connected with a suitable 55 support with its open side normally closed by a coacting movable member, and having an opening in the outer face to receive and support a cartridge, a safety cap slidingly connected with the casing and having a recess in which the head of the cartridge is seated and having an opening in line with the head when the cap is in operative position, a stop for locating the cap in operative position, means for holding the cap 60 and casing in proper relation, a resilient member mounted on the casing and a firing pin carried by the member and to be actuated thereby to enter the cap-opening and discharge the cartridge. 65

ORRIE C. STROHM.
